S. Presbrey, Jr.,

Turning Regular Forms.

Patented July 26, 1832.

July 26, 1832

Simon Prestrey, Junr. of Leiston in the County
of Suffolk & State of Massachusetts.

Letters Patent.

The Schedule referred to in these Letters Patent, and making
part of the same, containing a description in the words of the said
Simon Prestrey Junr. himself of his improvement in the method, by
means of a revolving cutter, or cutters, of finishing, equalizing and
finishing the ends of spools or bobbins used in spinning.

To all persons to whom these presents shall come, Simon
Prestrey Junr. of Leiston in the County of Suffolk & State of
Massachusetts. Cotton Manufacturer sends greeting. —

Be it known that I the said Simon Prestrey, Junr. have in-
vented and applied to use a new and useful method by means
of a revolving cutter or cutters of finishing, equalizing & finishing
the ends of bobbins of spools used in spinning, specifically
the words following, viz. It is well known that wooden
bobbins or spools are liable to draw irregularly - filling up une-
qually and often breaking the thread or yarn - the cause is
not often readily perceived and much time is lost before the
bobbin can be adjusted to run well; the principal cause is to be
found in a want of true-ness of the bobbin at the end on which
it rests - which may happen by the common method of making
them or by warping afterwards. —

The application of a revolving cutter or
cutters to enable the maker to finish the end of the bobbin in a
uniform and exact manner, and the spinner to correct and
repair such as may have changed by warping is the object
of this invention. Into the mandrel of a common turn-
ing lathe I fit a pine or mannaid of the size of the spindles
on which the bobbin runs, with cutters having thin edges

at right angles with the pin or mandrel to suit the required form of the bobbin. The cutters are forged from one piece of steel with a neck or hub to make a wheel, arm, or spoke to the pin or mandrel, & fastened with a strong pin so as to turn with it. They are about three-fourths of an inch wide and set at an oblique angle with the circle of revolution, so that only one, or two cutters are used. I have caps secured on the face, on the principle of a double iron plane iron.

To use the aforesaid cutters, they are set revolving at a speed such as is commonly used for turning wood. The bobbin is then put on the mandrel & held in the hand to prevent it from turning, at the same time pressing it against the cutters, which will reduce all inequalities.

In using these cutters in the making of bobbins, I propose to make it the first process, after the blocks of wood are bored and prepared for the latter to receive the last finish. The counter sink there made in the end of the block according to direct the workman in reducing it to its proper diameter. I have described the aforesaid cutters as being fitted to a common turning lathe, but the pin or mandrel of the cutters may be of sufficient length to receive a wheel or pulley and be fitted to some in a standard.

The cutters being connected by a neck or hub as before mentioned, can be withdrawn from the mandrel for the purpose of sharpening or of exchanging for those of a different angle if required.

What I claim as new and of my invention is the application of the aforesaid revolving cutters or cutters or any modification thereof, to the making or shaping of all kinds of bobbins or spools used in spinning.—

In testifying that the above is a true specification of my said improvement as above described, I have
